UNITED STATES PATENT OFFICE.

CHARLES W. WHITE, OF WACO, TEXAS.

MATTRESS-MAKING MACHINE.

SPECIFICATION forming part of Letters Patent No. 679,809, dated August 6, 1901.

Application filed March 11, 1901. Serial No. 50,537. (No model.)

To all whom it may concern.

Be it known that I, CHARLES W. WHITE, a citizen of the United States, residing at Waco, Texas, have invented certain new and useful 5 Improvements in Mattress-Making Machines, of which the following, taken in connection with the accompanying drawings, is a specification.

The invention to be hereinafter described 10 relates to mattress-making machines, and more particularly to that type thereof wherein the material to be placed in the tick is assembled and brought to the desired shape in a suitable frame and thereafter bodily moved 15 into the tick, which is suitably supported to receive it.

One of the objects of my present invention 20 is to provide a mattress-making machine whereby the stuffing material for the tick may be brought to the proper form and shaped up 25 into any convenient size, both as to length and width, in a suitable shaping and forming frame and then after being compressed be bodily moved into the tick without liability 30 of disturbing the shape and contour of the stuffing material.

Other objects of the present invention are 35 to simplify the construction and arrangement of parts to enable the above-defined operations to be easily and readily carried out, either by hand or power, to provide a form of compression-frame and operating mechanism therefor whereby the stuffing material may be readily and efficiently compressed to the required 40 amount, to provide means for forcing the forming and shaping frame into the tick with the stuffing material and to withdraw it therefrom, and to provide a general improved construction of parts whereby mattresses may be 45 quickly and easily made having well-defined corners.

With the above objects in view the invention consists of the parts and combinations, as will be hereinafter more fully described and 45 then definitely pointed out in the claims.

In the drawings, Figure 1 is a side elevation 50 of a mattress-making machine embodying my invention, some of the parts being broken away and the compression-frame being shown partly raised. Fig. 2 is plan view thereof with the compression-frame and its operating and attached mechanism omitted to better

show the construction of the main supporting-frame and the shaping or forming frame. Fig. 3 is an end view looking in the direction of 55 the arrow, Fig. 1, with the compression-frame in its lowered position and the lower tick-holding member omitted to better disclose the construction of slatted apron and its carrying-sprockets. Fig. 4 is a detail section on line 60 xx , Fig. 1. Fig. 5 is a detail side view showing a portion of the outer end of the shaping or forming frame resting upon the slatted apron with the lock or latch disengaged from between the slats. Fig. 6 is a view similar to 65 Fig. 5, except that the lock or latch is shown in engagement between the slats. Fig. 7 is a plan view of the compression-frame detached. Fig. 8 is a side or edge view thereof. Fig. 9 is an enlarged sectional view of one edge of 70 the compression-frame on the line yy , Fig. 8, showing the manner of engagement between the main and adjustable sections of said compression-frame.

The main supporting-frame for the operating parts of the machine comprises suitable uprights A A B B, joined by the side pieces A', suitably secured thereto and preferably braced in any desired manner to constitute 75 a convenient and stable framework. 80

Mounted in suitable bearings formed in the brackets B' at the head end of the machine is a shaft B², carrying the sprocket-wheels B³ B³ and operable from any usual source of power, as by the crank B⁴, through a suitable 85 chain of gears or pinions B⁵ and B⁶. Carried in suitable bearing B⁷, at the opposite end of the machine, is the shaft B⁸, having sprocket-wheels B⁹, corresponding to the sprocket-wheels B², and on and between these pairs of 90 sprocket-wheels are the sprocket-chains B¹⁰, connected by slats C', thus constituting the slatted apron C, which forms the bottom of the main supporting-frame. In order to compensate for any stretch or wear in the apron 95 C, the bearing carrying the shaft B⁸ is made adjustable in any usual or suitable manner, as by the adjusting-screw B¹¹.

Secured to the uprights A A are the rack-plates a, provided with the central teeth a' 100 and side channel-ways a² a², Figs. 3 and 4, the latter being engaged by suitable flanges a³ a³, formed on or made as a part of the bearing-blocks A² and A³, carrying the shafts A⁴

and A⁵, respectively. The bearing-blocks A² and A³ are connected together, so as to move in unison, by the links A⁶ A⁶, suitably bolted thereto at a⁴ a⁴. The bearing-blocks A² A² are preferably slotted, as shown in Fig. 3, and through such slots a⁵ project the rack-pinions A⁷ A⁷, fixedly secured to the shaft A⁴ and engaging the rack-teeth a' of the racks a. Fixed to one end of the shaft A⁴ is a hand-wheel A⁸, by which the shaft may be turned, and also secured to said shaft is a ratchet-wheel A⁹, adapted to be engaged by a pawl A¹⁰, pivoted to the bearing-block A², whereby rotation of said shaft in one direction may be restrained.

It will be evident from the construction thus far described that rotation of the shaft A⁴ by the hand-wheel A⁸ in the direction of the arrow, Fig. 1, will cause the bearing-blocks A² and the connected bearing-blocks A³, together with the shaft A⁵, to be raised, and upon engagement of the ratchet-wheel A⁹ and pawl A¹⁰ the said parts will be maintained in such elevated position.

25 Journalled upon the shaft A⁵, so as to rise and fall therewith, is the compression-frame, comprising a fixed or main section D and an adjustable section D', the fixed section D being provided with bearings d, hung upon the shaft A⁵, and with side projections d' or other form of slideways, which are embraced by suitable guide-plates d², secured to the upturned edges d³ of the adjustable section D' by the bolts or other desired securing means 35 d⁴. The upper flanges of the guide-plates d² are received under a member of the angle-iron d⁵, secured to the fixed or main section D, and are adapted to be clamped in any desired position of adjustment by the clamp-screws or other securing means d⁶. Thus it will be seen that the compression-frame is adjustable in the direction of its length within wide limits either in the formation of mattresses of widely-different dimensions or to 45 enable the machine to be put up in rooms or houses where the height of ceiling is limited, as will more fully appear.

In practice I have found it advantageous and desirable to form the fixed or main section D of suitable timbers or boards secured together and to form the adjustable section D' of metal, as indicated in Figs. 7, 8, and 9, having an end reinforcing-piece d^{8x}; but while I prefer this form of construction it is 55 to be understood that my invention is not limited in this respect and any desired modification can be made therein within the scope of my invention, and likewise other clamping and adjusting means may be employed for 60 the adjustable section, as will be obvious.

During the formation of the stuffing material in the forming or shaping frame, to be hereinafter described, the compression-frame is turned on its bearings d into an upright or 65 vertical position, and in order to effect this movement the fixed or main section of the compression-frame is provided near its free

end with an eyebolt d⁷, to which a cord, rope, or chain d⁸ is secured at one end and which then passes over a guide-pulley d⁹, secured to the cross-bar d¹⁰ at the top of the uprights A and has its other end connected to a winding-drum d¹¹, secured to the shaft A⁵. The said shaft A⁵ is provided with a hand-wheel d¹², by which it and the drum may be rotated 75 to wind up the rope or cord d⁸, and in order to hold the compression-frame in desired raised position the said shaft A⁵ is further provided with a ratchet-wheel d¹³, which is engaged by a pawl d¹⁴, pivoted to the bearing-block A³. Thus it will be seen that while the compression-frame is loosely journaled upon the shaft A⁵, so as to have its free end raised by means of the drum d¹¹ and rope or cord d⁸, it will also be raised or lowered bodily 80 or have its journaled end raised or lowered through the rack and pinions and upper shaft A⁴, as hereinbefore described.

The main supporting-frame has its ends open—that is, the side pieces A' are not joined 90 by corresponding end pieces—and in order to prevent the stuffing material from being forced through the opening thus left at the head of the machine during the time the material is being assembled for a mattress I 95 provide the compression-frame with an extension d¹⁵, which when the compression-frame is raised effectually closes the head end of the machine above the apron C, and when the frame is lowered said extension 100 bridges the space between the compression-frame and the adjacent end of the tick-holder, as will hereinafter more fully appear.

Secured to the uprights A A are the brackets E E, to which the brackets E' E' are adjustably secured by the bolts e e passing through the horizontal and vertical slots e' e² in said brackets, respectively, as will be clear from Fig. 1. Joining the brackets E' E' on opposite sides of the frame is the rod or other form of supporting-piece e³ and by which the lower member of the tick-support is carried, said member, as more clearly indicated in Fig. 2, comprising a fixed section E² and a sliding or telescoping section E³, said section E³ being connected to said rod e³ by the sliding clips e⁴ e⁴. The upper member of the tick-support is carried from the bearing-block A³, as indicated in Figs. 1 and 3, being connected thereto by the adjustable arms f' and f², clamped in adjusted relation by any usual form of bolt f³, passing through the slots f⁴. Extending between the arms f' f' on opposite sides of the machine is a rod f or other desired form of support, and secured thereto 125 and to one of the arms f' is the fixed section F of the upper member of tick-holder, the other section F' of the tick-holder being slidingly connected to the rod f or other support by clips f⁵ f⁵, whereby it may be adjusted or telescoped with relation to the fixed section. The detail form of construction of the tick-holder may be varied as desired, it only being necessary that the upper and lower

members may be adjusted with relation to each other to form mattresses of different thicknesses and that the sections of each member may be adjustable, so as to form mattresses of varying widths. In the present instance it will be noted that the lower member of the tick-holder is adjustable with relation to the slatted apron both vertically and horizontally to bring the tick into proper relation thereto and that the upper member, being carried by the bearing-blocks A³, is automatically adjustable therewith during the compression of the stuffing material, as will more fully appear hereinafter. The slotted arms f' and f² enable the upper member to be adjusted with relation to the plane of the compression-frame in a horizontal and vertical direction, and the space between the end of the upper member and the said frame is bridged or closed when the compression-frame is lowered by the extension d¹⁵ on said frame.

Loosely sustained with the side pieces A' A' of the main supporting-frame and adapted to rest upon the slatted apron C is my improved shaping or forming frame, (designated in general by G.) This frame comprises two side boards g g and intermediate slats or boards g' g² g³ g⁴, &c., extending substantially the full length of the supporting-frame, as shown more clearly in Fig. 2, several of said intermediate slats or boards—as g⁴, g⁵, and g⁶, for instance—being held in fixed relation to each other by one or more braces g⁷, secured to the slats or boards by pins, screws, nails, or the like g⁸, while the remaining slats are adjustable toward and from the fixed slats and may be held in adjusted position by any desired means—that, for instance, shown in Fig. 2, comprising a tube g⁹, secured to the fixed slats g⁴, g⁵, and g⁶ and into which telescopes the rod g¹⁰, secured to the slat g' and held in position by the set-screws g¹¹. While I have selected this as one form of means for adjusting the width of the shaping or forming frame, it is to be understood that I am not limited thereto, but that any suitable means for effecting such adjustment may be employed.

Secured to the side boards at h h is the push-board or ram H, by which the material after having been shaped in the shaping or forming frame G is forced into the tick. This push-board or ram is preferably made in two parts, as shown, and connected adjustably at the overlapping ends of the two parts by the bolts h' h', so that as the width of the frame is adjusted the push-board or ram will also be adjusted to the necessary extent. It is evident that unless some provision were made for varying the position of the push-board or ram toward or from the end of the shaping or forming frame the mattresses made on any one machine would all be the same length, whereas it is desirable that any length of mattress may be formed. One way of effecting this adjustment would be, of course, to vary the position of the push-

board or ram itself; but I have found in practice that a ready means of effecting the same result is by the use of a loose or dummy push-board H', which, as shown by dotted lines, Fig. 2, is adjustable to suit the width of shaping or forming frame, and interposing between it and the push-board H a series of loose pieces or dummies h² h², sufficient in number to secure the length of mattress desired. It is evident from this construction that in making a short mattress the stuffing material is all disposed in the shaping or forming frame between the head of the machine or extension d¹⁵ of the raised compression-frame and the dummy push-board H' and that when the material is to be pushed into the tick the dummy push-board serves as the ram or pusher; but should a full-sized mattress be desired the dummy push-board H' and the loose pieces or dummies h² h² are removed and the material then occupies the full space between the extension d¹⁵ and the push-board or ram H.

It is intended in this embodiment of my invention that the material shall be arranged and compressed within the shaping or forming frame, which rests upon the slatted apron C, and that such frame carrying the material shall be forced into the tick and then be withdrawn, leaving the material in perfect form in the tick, and to effect this movement of the shaping or forming frame I have provided the following mechanism:

Secured to the ends of the fixed slats g⁴ g⁵ g⁶ is one leaf k of the hinge K, the other leaf k' of which carries an angle-iron k². Likewise to the ends of each of the adjustable slats g' g² g³ is secured one leaf of a hinge in similar manner, while to the other leaf thereof is adjustably connected by the cap-screws k³ the slotted angle-iron K', adjustably connected also to the angle-iron k², whereby the slats may be readily adjusted toward and from each other and yet the angle-irons k² K' be turned either to the position of Fig. 5, out of engagement between the slats C' of the apron C, or to the position of Fig. 6, where they are shown in engagement between the slats of the apron. From this construction it will be evident that when the angle-irons are turned as in Fig. 6 and the slatted apron C moved in the direction of the arrow, Fig. 6, to feed the stuffing material into the tick the shaping or forming frame will be carried with it; but when the said angle-irons are turned as in Fig. 5 the said frame may be withdrawn over the slats. To effect this last result, I have mounted in suitable bearings m m on the end of the main supporting-frame a shaft M, carrying a drum m' and a hand-wheel m², by which it may be turned and have connected to the shaping or forming frame G, by means of suitable bolts m³ m³, a yoke O, to which is joined one end of a cord or rope P, which passes around and is adapted to be wound upon the drum m'. Thus it will be seen when the angle-irons are in the position shown in Fig. 5

if the shaft M is turned the frame G may be moved over the slats in the direction of the arrow, Fig. 5, and to render such movement more easy and avoid excessive friction I have 5 provided the said frame with rollers p p, one or more of which may be carried by a rod p', slidingly connected to the adjustable slats g', g², g³, g⁴, g⁵, and g⁶, as shown in Fig. 2. I may, if desired, provide a handle p⁸ for raising and lowering the angle-irons K' k², or any usual device may be employed for this purpose.

In order that the shaping and forming frame may be rigidly sustained to support the stuffing material during formation of the mattress and during compression thereof, I have deemed it desirable to provide for the adjustment of the slats from one side of the said frame toward the other and to support the 15 frame upon the apron C, with one side board g sustained against an auxiliary side piece R. This auxiliary side piece R is carried by adjusting-rods r r, which pass through one of the main side pieces A' of the main supporting-frame, and is held in adjusted position by suitable set-screws or clamping-bolts r' r', as will be clear from Fig. 2. In adjusting the machine for making a mattress narrower than the width of the main frame the shaping or 20 forming frame is pushed against one of the side pieces A' and the width of said frame then adjusted by movement of the slats g' g² g³ toward the fixed slats, the slats being then held in this adjusted relation by the set-screws 25 g¹¹ g¹¹ or other means. The auxiliary side piece R is then brought to bear against the side of the shaping or forming frame and clamped in position by the set-screws r' r', and the upper and lower members of the tick- 30 holder are adjusted to the required width, as 40 will be evident.

While I have described the above construction in its details as the preferred embodiment of my invention, it is to be understood 45 that I do not regard myself as limited to the precise construction specified and that the same may be varied within the limits of one skilled in the art without departing from the spirit of my invention.

50 The operation of the device is as follows: The shaping or forming frame G is placed within the supporting-frame upon the slatted apron, and the width of said frame G is then adjusted to the required width of mattress 55 desired. The auxiliary side piece R is then moved into contact with the side board g of the frame G, and the push-board H and other adjustable features of the frame are clamped in their adjusted position. Likewise the upper and lower members of the tick-holder are 60 adjusted to the desired width corresponding to that of the frame G. The compression-frame is then raised by turning the shaft A⁵, and the extension d¹⁵ then closes the forward 65 end of the main frame and acts as the front board of the frame G, into which the stuffing material is to be placed. If the length of the

mattress is to be less than of the standard size, (indicated by the position of the push-board H,) the dummy push-board H' is placed in position with a sufficient number of loose pieces or dummies h² interposed between it and the main push-board to secure the proper length of mattress, after which the stuffing material is placed within the rectangular frame thus defined by the shaping and forming frame and the extension d¹⁵ on the end of the compression-frame. When sufficient material has been placed within the shaping and forming frame, the compression-frame is lowered upon the 70 material, and its adjustable section being adjusted to the length of mattress to be produced the compression-frame is forced down and clamped in place by the clamps Q Q, which will engage suitable stops, as q, on the compression-frame or suitable cross-pieces, not necessary to show. The forward end of the compression-frame is then forced down to compress the material by means of the rack and pinions a and A⁷, and when the requisite degree of compression is reached the compression-frame is held in its position at the forward end of the pawl and ratchet A⁹ and A¹⁰. The tick having been placed over the upper and lower members of the tick-holder and the angle-iron k² being in position as indicated in Fig. 6, the slatted apron C is moved through its train of gearing from the hand-crank B⁴ or other suitable driving means, whereupon the entire shaping or forming frame G and the compressed stuffing material are forced from the main supporting-frame between the members of the tick-holder into the tick, the extension d¹⁵ at such time bridging the space between the upper member of the tick-holder 95 and the end of the compression-frame. The shaping and forming frame is then withdrawn 100 from the tick by means of the rope or cord P and shaft M, as will be evident, the angle-iron k² being first turned into position indicated by Fig. 5 to disengage it from between the slats of the slatted apron. 105

Having thus described my invention, what I claim, and desire to secure by Letters Patent, is—

1. In a mattress-making machine, the combination of a main frame, a compression-frame pivotally mounted in said main frame, means for raising and lowering the pivoted end of said compression-frame, and devices movable with said means and operable independent thereof for raising and lowering the free end of said compression-frame.

2. In a mattress-making machine, the combination of a main frame, a compression-frame pivotally mounted in said main frame, means for raising and lowering the pivoted end of said compression-frame, devices movable with said means and operable independent thereof for raising and lowering the free end of said compression-frame and means for securing the free end of the compression-frame upon the material to be compressed.

3. In a mattress-making machine, the com-

5 combination of a main frame, a compression-frame comprising a fixed section pivotally mounted in the main frame and an adjustable section movable lengthwise of the fixed section and means for securing the sections in adjusted relation.

4. In a mattress-making machine, the combination of a main frame, a compression-frame pivoted therein, and comprising a fixed 10 and an adjustable section movable lengthwise of the fixed section, means for securing said sections in adjusted relation, and means for independently raising and lowering the free and pivoted ends of said frame.

15 5. In a mattress-making machine, the combination of a main frame, a compression-frame pivoted therein at the exit end of the main frame, means for raising and lowering the free end of the compression-frame, devices for securing said end upon the material 20 to be compressed, means to thereafter force the pivoted end of said compression-frame downward to compress the material, and a tick-holder one member of which is connected 25 and movable with the pivoted end of the compression-frame.

6. In a mattress-making machine, the combination of a main frame having an open end, a compression-frame pivoted therein, and provided with an extension to close the open end 30 of the main frame when the compression-frame is raised, and means for raising and lowering the free end of said compression-frame.

7. In a mattress-making machine, the combination of a main frame, a tick-holder supported and spaced therefrom, a compression-frame pivoted in the main frame and provided with an extension to close the end of the main frame when the compression-frame 40 is raised and to bridge the space between the upper member of the tick-holder and compression-frame when the latter is lowered upon the material, and means for raising and lowering said compression-frame.

45 8. In a mattress-making machine, the combination of a main frame, a shaft supported thereby, a compression-frame pivotally mounted upon said shaft, means operable from said shaft for raising and lowering the free 50 end of said compression-frame, a tick-holder spaced from and extending beyond said shaft the upper member of which is movable with said shaft, and means for positively raising and lowering the said shaft and the pivotal 55 end of the connected compression-frame and upper member of the tick-holder.

9. In a mattress-making machine, the combination of a main frame having uprights, racks secured to said uprights, a shaft having pinions engaging said racks, means for restraining the shaft from rotation in one direction, a second shaft, devices connecting the two shafts to cause them to move in unison, a compression-frame hung from said second shaft, and means operable from said second shaft for raising and lowering the free 60 end of the compression-frame, whereby the

free end of said compression-frame may be lowered and thereafter the opposite end may be forced downward to compress the material. 70

10. A compression-frame comprising fixed and adjustable sections, the latter being movable lengthwise of the former to vary the combined length of the two sections, means for securing them in adjusted relation, and an 75 extension secured to the fixed section.

11. In a mattress-making machine, the combination of a main frame provided with a slatted apron, a compression-frame pivotally mounted on the main frame, and a separate 80 and independent shaping or forming frame to receive the stuffing material and adapted to be supported on the apron of the main frame, said shaping and forming frame being provided with means for engagement between the slats of the apron and means for adjusting the shaping and forming frame to the size of mattress desired.

12. In a mattress-making machine, the combination of a main frame provided with a 90 slatted apron, an auxiliary side board adjustably connected to said main frame, a compression-frame pivotally mounted on the main frame, and a separate and independent shaping or forming frame to receive the stuffing 95 material and adapted to be supported on the apron of the main frame, said shaping and forming frame being provided with means for engagement between the slats of the apron, and means for adjusting the shaping and forming frame to the size of mattress desired. 100

13. In a mattress-making machine, the combination of a main frame having an open end provided with a slatted apron and means for operating it, a compression-frame pivotally mounted on the main frame and provided with an extension to close the open end of the main frame when the compression-frame is in raised position, a shaping or forming frame adapted to rest upon the slatted 105 apron to receive the stuffing material and means for causing the shaping and forming frame to move with the apron to carry the material into the tick.

14. In a mattress-making machine, the combination of a main frame provided with a slatted apron and means for moving the apron, of a shaping or forming frame adapted to rest upon the apron to receive the stuffing material, and means on said shaping and 120 forming frame for engagement between the slats of the apron for connecting the said shaping or forming frame to said apron and to cause it and the stuffing material to be moved into the tick. 125

15. In a mattress-making machine, the combination of a main frame provided with a slatted apron and means for moving the apron, of a shaping or forming frame adapted to rest upon the apron to receive the stuffing material, and means for engagement between the slats of the apron for connecting the said shaping or forming frame to said apron and to cause it and the stuffing material to be

moved into the tick, and means independently of the apron for thereafter withdrawing the shaping or forming frame from the tick.

16. In a mattress-making machine, the combination of a main frame provided with an apron and means for moving said apron, of a shaping and forming frame adapted to rest upon said apron and having a push-board or ram, connected to and forming part of the shaping and forming frame and means on said shaping and forming frame to engage the slatted apron for detachably connecting the shaping and forming frame to said apron to cause it and the material contained therein to be carried into the tick.

17. In a mattress-making machine, the combination of a main frame provided with a slatted apron, an auxiliary side piece or board adjustably connected to the main frame, a shaping or forming frame independent of the auxiliary side piece or board and adjustable as to width and adapted to rest upon said apron between a side piece of the main frame and the auxiliary side piece, and means for detachably connecting the shaping or forming frame between the slats of the apron to cause it and the material therein to be carried into the tick.

18. In a mattress-making machine, the combination of a main frame provided with a slatted apron, an auxiliary side piece or board adjustably connected to the main frame, a shaping or forming frame independent of the auxiliary side piece or board and adjustable as to width and adapted to rest upon said apron between a side piece of the main frame and the auxiliary side piece, an adjustable push-board or ram connected to the shaping or forming frame, and means connected to the shaping and forming frame for detachably connecting the shaping or forming frame between the slats of the apron to cause it and the material therein to be carried into the tick.

19. A shaping or forming frame, comprising a series of slats some of which are adjustable toward and from the others, side pieces arranged at the sides of said series of slats, an adjustable push-board or ram connecting said side pieces, an angle-iron hinged to said slats, and means for securing the slats in adjusted relation.

20. A shaping or forming frame, comprising a series of slats some of which are adjust-

able toward and from the others, rollers disposed between said slats, side pieces arranged at the sides of said series of slats, an adjustable push-board or ram connecting said side pieces and means for securing the slats in adjusted relation.

21. In a mattress-making machine, the combination of a main frame provided with a slatted apron and operating means and an adjustable tick-holder, a compression-frame pivoted in said main frame and adjustable lengthwise, a shaping or forming frame adapted to rest upon said slatted apron and adjustable in width, a push-board or ram carried by said frame, and means connected to said shaping and forming frame and adapted to be engaged between the slats of the apron to cause the said frame to move therewith and carry the stuffing material and be itself carried into the tick.

22. In a mattress-making machine, the combination of a main frame having an open end, a compression-frame pivoted therein and provided with an extension to close the open end of the main frame when the compression-frame is in raised position, a shaping or forming frame provided with a push-board or ram, a dummy push-board or ram, and a series of loose pieces or dummies adapted to be inserted between the two push-boards to vary the length of the mattress to be made and means for moving the shaping or forming frame and the material carried thereby into the tick.

23. In a mattress-making machine, the combination of a main frame, a compression-frame having an open end pivoted therein and provided with an extension to close the open end of the main frame when the compression-frame is in raised position, a shaping or forming frame provided with a push-board or ram, a dummy push-board or ram, and a series of loose pieces or dummies adapted to be inserted between the two push-boards to vary the length of the mattress to be made and means for moving the shaping or forming frame and the material carried thereby into the tick, and means for withdrawing the shaping or forming frame from the tick.
